UNITED STATES PATENT OFFICE.

WALTER P. MURPHY, OF CHICAGO, ILLINOIS, ASSIGNOR TO P. H. MURPHY COMPANY,
OF PARNASSUS, PENNSYLVANIA, A CORPORATION OF PENNSYLVANIA.

CAR-ROOF.

1,250,624.

Specification of Letters Patent. Patented Dec. 18, 1917.

Application filed December 6, 1915. Serial No. 65,174.

To all whom it may concern:

Be it known that I, WALTER P. MURPHY, a citizen of the United States, and a resident of the city of Chicago, in the county of Cook and State of Illinois, have invented a new and useful Improvement in Car-Roofs, of which the following is a specification.

This invention relates to roofs composed of heavy gage steel plates which are securely riveted or otherwise rigidly attached together and to the car frame, and is an improvement in car roofs of the type shown in my Patent No. 1,133,495, dated March 30, 1915. This application contains subject-matter divided out of my pending application, filed November 6, 1915, Serial No. 59,938.

The objects of the invention are to stiffen the car roof and sides by means of the shape and arrangement of the carlines and roof plates, to stiffen the roof plates and prevent sweating of the roof plates on their under sides and provide a smooth ceiling without materially diminishing the headroom in the car, and to decrease the weight of the roof 25 without impairing its strength and durability.

The invention consists in utilizing plates of narrower width and heavier gage metal near the middle of the car than at the ends thereof and in capping the seams with exterior carlines, which are thus more closely spaced in the middle of the car than at its ends; also, in providing heavy gage metal seam covers or outside carlines having a greater vertical depth at the ridge than at the eaves and lateral base flanges of greater width at the eaves than at the ridge and riveting them securely to the frame of the car at their eaves ends; also, in the eaves end 40 construction of the seam covers to make them weatherproof; also, in sheathing the under sides of the roof plates with thin wood boards supported upon the side plates and by means of hangers from the roof itself to 45 keep the roof plates from sweating and to assist the roof plates in carrying the loads to which they may be subjected; and also in the details of construction hereinafter described.

Further objects of the invention appear in connection with the description of the car roof embodying the invention shown in the accompanying drawings, and what is claimed herein as the invention is stated in 55 the appended claims.

In the drawings, wherein the same reference characters designate like parts in the several views,

Figure 1 is a plan view of the middle portion of a car roof embodying the invention, 60 partly broken away to disclose the construction of the under portion;

Fig. 2 is a cross-section of the same on the line 2—2 in Fig. 1;

Fig. 3 is a perspective view of an end 65 portion of a seam cover; and

Fig. 4 is a longitudinal sectional view of Fig. 1 on a line between the ridge and the eaves.

The car shown in the drawings has Z-bar 70 side plates 11 arranged with their webs vertical and their top flanges facing inward. An angle bar 12 is secured to the outer side of the web of each side plate, with its horizontal flange up and facing outward, forming an eaves molding for the roof. The tops of the angle bars 12 are spaced slightly above the tops of the side plates 11. The metal roof plates 13, 14 are arranged crosswise of the car, extending from eaves to eaves and 75 resting at their ends upon the top flanges of the angle bars 12, and are arched upward at their middles, thereby forming a curved ridge. The roof plates 13 at the ends of the car are made of greater width and lighter 80 gage metal than the roof plates 14 at the middle of the car, which are made of heavy gage metal and which are extra well secured to the eaves angle bars 12, so as to more effectively brace the frame and resist the 85 stresses due to the racking and twisting of the car. The side margins of the roof plates are flanged up and laid in contact alongside of each other; and metal seam covers 15 are placed one over each pair of upturned roof 90 plate flanges and are rigidly secured thereto by rivets or other suitable fastening means. 95

The seam covers 15 are of inverted U-shape with lateral flanges 16 projecting out from the lower edges of their side walls and 100 resting on the roof plates. Their ends are closed by lengthwise projections or tabs 17 from one side wall, which are bent across the space between the side walls and riveted to the other side wall, as shown in Fig. 3. 105 The top edges of the seam covers project over the folded end tabs to cover their upper edges and make a tight joint. The seam covers are of greater depth at the ridge than at the eaves, each one decreasing in 110

depth uniformly from the middle toward the ends; and the lateral flanges 16 are wider at the eaves than at the ridge, each flange growing narrower uniformly from 5 the ends to the middle of the seam cover. The ends of the flanges 16 are riveted or otherwise securely fastened to the eaves angles 12.

Their flanged and tapered shape makes 10 the seam covers very stiff against both vertical loads on the roof and horizontal forces tending to spread or twist the side plates, and enables the seam covers to function as outside carlines. The seam covers and the 15 heavy gage roof plates 14 at the middle of the car together constitute a very stiff and solid brace across the top of the car at the doors, and hold the side plates from spreading or moving endwise with respect to each 20 other.

The wood running boards 18 are fastened to metal running board saddles 19 which are supported on and secured to the seam covers 15 along the ridge. A sheathing or lining 20 25 of thin wooden boards is arranged beneath the roof plates to prevent condensation of moisture, or sweating, on their under sides. The ends of the lining boards rest on the top flanges of the side plates, and the middle portions are held up to conform to the 30 arch of the roof plates by metal rods or bars 21 which are suspended from the roof by means of hangers 22 projecting down from between the roof plate flanges at the ridge. 35 The hangers 22 are riveted or otherwise securely fastened to the flanges of the roof plates and seam covers. The arched form of the lining boards and their manner of support gives them sufficient stiffness to support 40 the lighter roof sheets between their edges.

From the foregoing description it is evident that this invention enables a very strong, light roof to be made, having ample 45 stiffness where required to brace the top of the side walls of the car. There are no rivet holes through the roof plates into the car, and the sheathing prevents sweating and stiffens the thinner roof plates at the 50 ends of the car.

The invention is not restricted to the particular shapes and arrangements of parts shown in the drawings.

I claim the following as my invention:

55 1. A car roof given a truss construction longitudinally as well as transversely of the car, composed of a plurality of plates running transversely of the car and rigidly secured together at their edges to act as a 60 unitary longitudinal girder, the truss conformation being secured by the use of plates of different gages, thicker gages of plates being placed in the middle of the car than at the ends.

65 2. A car roof comprising roof plates ex-

tending crosswise of the car and rigidly secured at their ends to the top of the side walls of the car, and stiffening members spanning from side to side of the car and secured to the outer edges of the roof plates, 70 the roof plates at the middle of the car being of heavier gage and narrower width than those at the ends of the car for bracing the car sides horizontally, and the stiffening members being spaced closer together at the 75 middle of the car than at the ends of the car, whereby the roof plates and stiffening members are better enabled to take care of the stresses occasioned by the weaving of the car.

80 3. A car roof comprising upwardly curved metal roof plates extending from eaves to eaves and having upstanding flanges along their side margins, and cover strips of inverted U shape with outwardly projecting flanges along the bottom edges of the side walls upwardly curved to conform to said roof plates and arranged over the adjacent flanges of said roof plates, said cover strips having a greater height at the ridge than 90 at the eaves of the roof and their bottom flanges having a greater width at the eaves than at the ridge of the roof, and means for securing said flanges and cover strips together to form a rigid joint, whereby said 95 roof plates and cover strips together constitute transverse supporting and stiffening members for the sides of the car.

4. A car roof comprising upwardly curved metal roof plates extending from eaves to 100 eaves and having upstanding flanges along their side margins, cover strips of inverted U shape upwardly curved to conform to said roof plates and arranged over the adjacent flanges of said roof plates, said cover 105 strips having a greater width at the eaves than at the ridge of the roof, means for securing said flanges and cover strips together to form a rigid joint, and continuous eave strips arranged lengthwise of said 110 roof under the eaves ends of said roof plates and rigidly secured thereto and to the ends of said cover strips, whereby said roof plates and cover strips together constitute a ribbed arch connecting said eaves strips 115 and thereby support the sides of the car laterally and stiffen them and the roof lengthwise of the car.

5. A car roof comprising upwardly curved roof plates extending crosswise of the car 120 and correspondingly curved stiffening members spanning the car from side to side and rigidly secured to the outside of said roof plates at their edges, lining boards extending across said car beneath said roof plates 125 and in contact therewith, said lining boards being supported on the sides of the car at their ends and bowed up against the under side of the roof sheets between their ends by hangers arranged between the edges of 130

said roof plates and supported by said stiffening members, whereby said lining boards act as arches to stiffen the roof plates.

6. A car roof comprising upwardly curved roof plates extending crosswise of the car and having their side margins flanged and secured together, the ribs thereby formed spanning the car from side to side, upwardly bowed lining boards extending across said car beneath and in contact with said roof plates, said lining boards being supported at their ends from the car sides, and suspended intermediate their ends from the car roof by hangers secured to the edges of said roof plates, and intermediate supports for the lining boards carried by said hangers, whereby said lining boards act as arches to stiffen said roof.

7. A self-supporting car roof comprising roof sheets having upturned side flanges, said roof sheets being arranged parallel to each other with their flanges extending crosswise of the car, seam covers having tops and side walls arranged over said pairs of adjacent flanges with their side walls

riveted to said flanges, hangers arranged between the flanges of adjacent sheets and secured thereto, the lower edges of said hangers projecting below said sheets and supporting longitudinal brace members, and roof lining arranged in sections beneath the roof sheets between said hangers and supported by said longitudinal brace members, whereby said seam covers and roof sheet flanges stiffen said roof at the seams and support said lining and roof sheets.

8. A car roof comprising roof plates extending crosswise of the car and rigidly secured along their ends to the top of the side walls of the car, and stiffening members spanning from side to side of the car at each roof joint, the sheets in the middle part of the car being narrower than those of the end portion of the car, whereby the stiffening members are closer together in said middle portion.

Signed at Chicago, Ill., this third day of December, 1915.

WALTER P. MURPHY.
